UNITED STATES PATENT OFFICE.

HARRISON H. EATON, OF CLEVELAND, OHIO.

DESIGN FOR A LACING-HOOK.

SPECIFICATION forming part of Design No. 33,108, dated August 21, 1900.

Application filed August 9, 1899. Serial No. 726,723. Term of patent 14 years.

To all whom it may concern:

Be it known that I, HARRISON H. EATON, a citizen of the United States, residing at Cleveland, in the county of Cuyahoga and State of Ohio, have invented and produced a new and original Design in Lacing-Hooks, of which the following is a specification, reference being had to the accompanying drawings, forming part thereof.

Figure 1 is a plan view of my new design in lacing-hooks. Fig. 2 is a plan elevation with the hook turned a quarter-way around to the right, and Fig. 3 is a plan elevation with the hook turned a quarter-way around to the left from an elevation corresponding to Fig. 1. Fig. 4 is a bottom view looking into the tabular shank.

The design is distinguished by the several features shown, comprising a tubular shank a slightly tapered, an ornamental collar *b* about the top of the shank, and a hook *c* of

cylindrical outline from base to point projecting directly out of the center and top of said collar, and having a compound curvature, as indicated between 2 and 2 in Fig. 3, 25 particularly, but seen also in other views, and 4 and 4 in Fig. 1 on the segment of a circle, the extremity of the hook lying outside the radius of the collar *b* in plan view, Figs. 1 and 4, and in a plan substantially parallel 30 therewith when viewed in elevation, Figs. 2 and 3, but having a slight dip in its neck, as seen most clearly in Fig. 3.

What I claim is—

The design for a lacing-hook, substantially 35 as herein shown and described.

Witness my hand to the foregoing specification this 29th day of July, 1899.

HARRISON H. EATON.

Witnesses:

H. T. FISHER,
R. B. MOSER.
